UNITED STATES PATENT OFFICE.

FRANK W. FELL, OF HAWORTH, NEW JERSEY.

DESIGN FOR A RIBBON.

Application filed May 7, 1925. Serial No. 13,340. Term of patent 3½ years.

To all whom it may concern:

Be it known that I, FRANK W. FELL, a citizen of the United States, residing at Haworth, in the county of Bergen, and State of New Jersey, have invented a new, original, and ornamental Design for Ribbons, of which the following is a specification, reference being had to the accompanying drawing, forming part thereof.

The figure is a plan view of a ribbon, showing my new design.

I claim:

The ornamental design for a ribbon, as shown.

FRANK W. FELL.
